UNITED STATES PATENT OFFICE.

GASTON W. MONTGOMERY, OF TORONTO, ONTARIO, CANADA, ASSIGNOR TO OXYGENATED STOVE AND HEATER COMPANY, LTD., OF TORONTO, ONTARIO, CANADA.

COOK-STOVE.

1,083,692.

Specification of Letters Patent.

Patented Jan. 6, 1914.

Application filed May 19, 1913. Serial No. 763,392.

To all whom it may concern:

Be it known that I, GASTON W. MONTGOMERY, a citizen of the United States, residing at Toronto, county of York, Province of 5 Ontario, Canada, have invented a certain new and useful Improvement in Cook-Stoves, and declare the following to be a full, clear, and exact description of the same, such as will enable others skilled in the art 10 to which it pertains to make and use the same, reference being had to the accompanying drawings, which form a part of this specification.

This invention relates to stoves for cooking purposes and has for its object a stove 15 in which both the heat from a gas burner and steam is used to cook with.

A still further feature is the transfer of the vapors arising from the foods and also 20 the steam to the combustion chamber of the gas burner.

In the drawings: Figure 1, is a vertical section on the line A—A of Fig. 2, a part 25 of the ovens being left in elevation to show the doors. Fig. 2, is a vertical section on the line B—B of Fig. 1.

A cabinet *a* is formed preferably of metal and is lined with heat-insulating material, such as asbestos, *b*. In my preferred form 30 of construction I support two sheet metal ovens *c* and *d* centrally within the cabinet, the oven *c* above the oven *d*. Each oven has a door *e* which opens downward. The hinges are preferably of a kind to hold the 35 door *e* horizontally when it is open. Access may be had to each oven through the heat-insulated closures *f* of the cabinet. These 40 closures have a beveled fit with the openings in the cabinet to insure tightness when closed.

Two water tanks *g* are supported in the interior of the cabinet, one adjacent to each oven. These tanks are fastened to a beveled edge closure *h* of the cabinet. The beveled 45 edge fits into a correspondingly beveled opening that insures an air-tight fit. A drainage cock *i* leads from the tank through the closure. A nipple *j* protrudes from one side of each oven. A short nipple *k* 50 protrudes from each water tank so that when the water tanks are placed their nipples slide into the over-nipples to form a passage between the oven and water tank. The ovens are supported by the interengaging

nipples, stay bolts *l* that connect with the 55 sides of the cabinet opposite the sides having the nipples and by the piping hereinafter described.

A burner is supported in the cabinet by legs *m*. It is formed into three chambers, 60 a gas chamber *n*, and two air chambers *o*, one above and the other below the gas chamber. The principal source of fuel for the burner enters the cabinet through the pipe *p* that leads to the gas chamber *n*. This 65 pipe *p* is controlled on the outside of the cabinet by the valve *q*. An air pipe *r* leads from the exterior of the cabinet up to a point above the burner where it divides and the two branches lead across the burner slightly 70 above it to a point beyond the rear wall of the ovens, then horizontally to the rear of the ovens near the bottom. The branch *s* leads into the oven *d*. The branch *t* leads into the oven *c*. On the opposite sides of 75 the ovens the pipe *u* connects with each oven and leads therefrom into each air chamber *o* of the burner by branches.

A stack *w* is located at the top of the cabinet.

The mode of operation is as follows: The 80 gas may be turned on and the burner ignited by opening the closure *z* of the cabinet. This heats the air in the cabinet and it rises and escapes through the stack *w*. More air 85 to take its place is drawn through the air pipe *r* and the branches *s* and *t* of the same into the ovens *c* and *d*. While passing through the branches *s* and *t* over the burner, the air is considerably heated so that it 90 passes into the ovens in a heated condition calculated to aid in the cooking. The air passes through the ovens and through the pipe *u* that goes into the air chambers *o* of the burner and furnishes the necessary oxygen 95 for the combustion of the gas entering through the gas pipe *p*. This circulation through the ovens carries off the vapors of the foods cooking. Some of these vapors may be quite combustible and hence fuel is 100 added to the usual fuel supply for a gas burner. Further, the combustion of these vapors entirely eliminates the odors of cooking. When the cabinet has been sufficiently heated by the burner, the water tanks *g*, 105 which are filled with water up to the level of the openings of the nipples *k*, begin to give off steam. This steam enters the ovens

through the nipple connections and is drawn into the circulatory current already described. This makes a current of steam and highly heated air. The heat of the steam penetrates deeply into the food stuff and the heated air, while penetrating less deeply, browns the food nicely. The steam in mixing with the highly heated air and passing through the heated piping and into the air 10 chambers σ of the burner, is superheated. On account of this superheated condition, when it reaches the burner, the steam is easily disassociated and furnishes fuel for the burner.

15 What I claim is:

1. In a gas cook-stove, a heat-retaining chamber, an oven therein, a gas burner for heating the oven, means for supplying steam to said oven, and means for directing air 20 from the outside of said heat-retaining chamber, conveying it to where it will be preheated by heat generated by the gas burner and then delivering it to said oven, and means for directing the steam and heated 25 air from said oven to the combustion chamber of said burner, substantially as described.
2. In a gas cook-stove, a heat-retaining chamber, an oven contained therein, a gas burner for heating the oven, means for supplying steam to said oven, and means for directing air from the outside of said heat-retaining chamber, adjacent to the flame of 30 said gas burner to heat the air and then directing the heated air to the oven, and finally directing said air and said steam from 35 said oven to the combustion chamber of said burner for combustion, substantially as described.
3. In a cook-stove, the combination of an 40 oven, a burner for heating the same, steam generating apparatus for furnishing steam to the oven, means for heating air, means for directing said heated air from the outside of the oven, through the oven where it 45 picks up steam and thence directing the air,

steam and vapors of the oven to the burner for combustion, substantially as described.

4. In a cook-stove, the combination of an oven, a burner for heating the same, steam generating apparatus operated by the burner 50 for furnishing steam to the oven, and means for directing preheated air into the oven where it picks up steam and vapors and for conducting the same to the burner for combustion, substantially as described. 55

5. In a gas cook-stove, a cabinet, an oven therein, a gas burner contained in the cabinet and adjacent to the oven, said gas burner being provided with a gas chamber and an air chamber, a gas pipe for supplying gas 60 to the gas chamber, a pipe leading from the oven for drawing off the gaseous contents of the oven and conducting it to the air chamber of the burner, and a conduit for drawing air from the outside of the cabinet, taking it to a position where it will be preheated then delivering it into the oven, substantially as described.

6. In a gas cook-stove, the combination of a cabinet, an oven supported therein, a water 70 tank also supported in a cabinet, a pipe leading from the water tank to the oven, a gas burner contained in the cabinet and adjacent to the oven, said gas burner being provided with an air chamber, a fuel pipe for 75 supplying fuel gas to the burner, a pipe leading from the oven for drawing off the gaseous contents of the oven and conducting it to the air chamber of the burner, and a conduit for drawing air from the outside of 80 the cabinet, the said conduit passing adjacent to the burner where the air is preheated and then passing into the oven, substantially as described.

In testimony whereof, I sign this specification in the presence of two witnesses.

GASTON W. MONTGOMERY.
